[57] CLAIM

The ornamental design for the pastry package, as shown and described.

DESCRIPTION

FIG. 1 is a perspective view of a pastry package showing my new design;

FIG. 2 is a first side plan view thereof;

FIG. 3 is a second side plan view thereof, 90 degrees from the first side plan view; the view from the opposite side of the container being the mirror image;

FIG. 4 is a third side plan view of the side opposite the first side view;

FIG. 5 is a bottom plan view thereof; and,

FIG. 6 is a top plan view thereof.
